UNITED STATES PATENT OFFICE

111,220

DESIGN FOR A DESK

Bayard E. Richardson and Richard W. Willey,
Grand Rapids, Mich.

Application February 7, 1938, Serial No. 74,929

Term of patent 7 years

To all whom it may concern:

Be it known that we, Bayard E. Richardson and Richard W. Willey, citizens of the United States, residing at the city of Grand Rapids, in the county of Kent and State of Michigan, have invented a new, original, and ornamental Design for a Desk, of which the following is a specification, reference being had to the accompanying drawing, forming a part thereof.

Fig. 1 is a front perspective view of a desk showing our new design, and

Fig. 2 is a rear perspective view of the same.

We claim:

The ornamental design for a desk, as shown.

BAYARD E. RICHARDSON.

RICHARD W. WILLEY.
